UNITED STATES PATENT OFFICE.

DANIEL P. KANE, OF ST. LOUIS, MISSOURI.

REVERSING DEVICE FOR ENGINES.

SPECIFICATION forming part of Letters Patent No. 328,787, dated October 20, 1885.

Application filed October 4, 1884. Serial No. 144,749. (No model.)

To all whom it may concern:

Be it known that I, DANIEL P. KANE, of the city of St. Louis, in the State of Missouri, have invented a certain new and useful Improvement in Reversing Devices for Steam-Engines, of which the following is a full, clear, and exact description, reference being had to the accompanying drawings, forming part of this specification.

10 Figure 1 is a side view of an engine having my device. Fig. 2 is an inside view of the oscillating valve, and Fig. 3 is a section of the same at 3 3, Fig. 2. Fig. 4 is a face view of the valve-seat. Fig. 5 is a longitudinal section at 5 5, Fig. 6, and Fig. 6 is a transverse section at 6 6, Fig. 5. Fig. 7 is a side view of the valve-chest with the cover removed, giving an outside view of the oscillating valve with parts of same broken away to show the 20 steam-ports and the course of the currents of live and exhaust steam. Fig. 8 is a side view of two slide-valves working in separate chests, and forming a modification of the oscillating valve, the other parts being substantially the 25 same in both. Fig. 9 is a transverse section at 9 9, Fig. 8.

A is the bed of an engine; B, the cylinder; C, the live-steam pipe, and D the exhaust-pipe.

30 E is the piston-rod; F, the cross-head; F', the connecting-rod; G, the crank-wheel, and H the crank-shaft.

I is the eccentric, and J the eccentric-rod.

K is the valve-chest, which may be cast in 35 one piece with the cylinder, or may be attached thereto. The valve-chest is bored longitudinally near the top and bottom to receive two plug-valves, L and L', which are closely fitted in said bores and which work endwise 40 therein. The outer ends of the plug-valves are connected to the opposite ends of a handle-lever, M, working on a fulcrum at N, the construction being such that as one valve is drawn outward the other is pushed inward.

45 O is a live-steam chamber or passage in constant communication with the steam-pipe C.

P are ports leading from the chamber O to the bores L², in which the valves L L' work. The valves L L' have angular or curved pas- 50 sages l, so made as to open communication be-

tween the ports P and ports Q Q', leading into the two chambers r r' of the oscillating valve R. This valve is cylindrical in form, and chambered out on the inner side, forming the two chambers r r'. These chambers are separated by a diametric partition, r², whose edge works with a steam-tight bearing against the valve-seat S. It is intended that the marginal flange r³ shall also have a steam-tight bearing upon the valve-seat, so that there cannot be 60 any escape of steam from the chambers r r' except through the steam-ports.

T T' are steam-ports leading directly into the ends of the cylinder and forming the cylinder-ports.

The valve R is sunk into a recess, U, of the steam-chest, of which the valve-seat forms the bottom. The valve R turns with a central gudgeon or stem, R', which has bearing in the cover or lid K' of the valve-chest K.

K² is a crank on the gudgeon, whose pin is engaged by the yoke J' of the eccentric-rod J.

In addition to the passages l the plug-valves L L' have transverse steam-passages l' which pass directly and diametrically through the valves in a horizontal direction, and which form communication between the ports Q Q' and the ports Q² in line therewith, and which are in communication with the exhaust-passage D.

The operation of the device is as follows: Supposing the valves L L' to be in the position shown in Figs. 1, 5, and 6, and the oscillating valve to be in the position shown in Fig. 7, the live steam will enter the chamber r of the valve R, through passage P l Q, and will enter the end of the cylinder nearest the crank-shaft through the port T, and will exhaust from the cylinder through the port T', and pass from the chamber r' into the exhaust-passage D, through ports Q' Q² and the valve-passage l'. When the eccentric, by movement of the valve R, throws the port Q into communication with port T' and the port T into communication with the port Q', the motion 95 of the piston is reversed.

To reverse the rotation of the crank-shaft, the position of the lever M is reversed, drawing out the valve L and pushing in the valve L'. Then the live steam will pass through pas- 100

sage or chamber O and enter the lower valve-chamber, r' , and exhaust from the cylinder through the chamber r .

In the modification shown in Figs. 8 and 9, 5 the construction is similar, except that two slide-valves are used in place of the oscillating valve. In this case the steam-chambers $r r'$ have a fixed partition between them (lettered r^2) in the same way as the oscillating partition of the oscillating valve. The valves R may 10 each consist simply of a flat plate sliding over and held to the valve-seat, and made by the action of the eccentric to alternately close and open the two cylinder-ports T T'. When the 15 parts are in the position shown, the chamber r is the live-steam chamber, and the chamber r' the exhaust-chamber. The valve-stems R' are connected to the opposite end of a lever, R ^{2} , which is oscillated by the eccentric-rod J. 20 The construction and operation of the valves L L' is exactly similar to that before described.

I claim—

1. An oscillating valve provided with two unconnected chambers and working on a seat 25 having two cylinder-ports and two other steam-ports, in combination with a valve interposed between the said steam-ports and the

live-steam and exhaust ports, for the purpose set forth.

2. The combination of steam and exhaust 30 ports, two reversing-valves coupled together to cause synchronous reverse movements, a steam-chest in communication, respectively, with the ports of the two reversing-valves, and ports in the steam-chest leading to the 35 ends of the cylinder, substantially as and for the purpose set forth.

3. The combination of the two valves L L', connected to the opposite ends of a lever, live- 40 steam port C, and exhaust D, a valve-seat having ports Q Q' and T T', and a valve or valves, R, constructed and arranged to operate substantially as and for the purpose set forth.

4. The combination of the two valves L L', 45 coupled together by lever M, the valve R, having two disconnected chambers, $r r'$, the valve-seat and valve-chest, and the valve ports and passages, substantially as and for the purpose set forth.

DANIEL P. KANE.
